UNITED STATES PATENT OFFICE.

JAMES P. MADDEN, OF BETHLEHEM, PENNSYLVANIA.

ENTRAINMENT GEARING.

Application filed August 25, 1925. Serial No. 52,260.

My invention relates to gearing, and more particularly to gearing of the connectible and disconnectible tumbler type, and it has for an object to provide apparatus of this character which shall operate automatically to connect and to disconnect the tumbler gear with the driven gear in consequence of rotation or cessation of rotation of the driving gear in a given direction.

In the application of auxiliary engines to the trucks of railway vehicles, for example, to tender trucks of locomotives, it has heretofore been proposed to have the driving shaft of such a motor or engine provided with a driving gear constantly in mesh with a tumbler gear, the latter gear being adapted to move to meshed and to demeshed positions with respect to a driven gear carried by a load-bearing axle. This general type of gearing is particularly suitable for this purpose; and two different systems have been proposed for securing the necessary shifting of the tumbler gear, the first system being one depending upon elastic fluid being admitted to an operating cylinder to secure the necessary shifting of the tumbler incident to energization of the driving motor or engine, and the second arrangement being where the tumbler gear automatically moves to meshed and to demeshed positions in consequence of the motor or engine being rendered effective and ineffective. My invention relates to a mechanism of the latter type; and it has for an object to provide a rocker gear element pivotally connected to a resilient supporting member and having resilient means to maintain the rocker member in a predetermined angular position with respect to the supporting means, the rocker member having teeth arranged at different radial distances from its axis and the tooth of minimum radial distance being adapted to engage between teeth of the tumbler when the latter is in its demeshed position.

A further object of my invention is to provide apparatus of the character referred to wherein dampening means shall be employed to check the movement of the tumbler and its carrier in a demeshing direction in order to avoid unnecessary clashing of the teeth of the tumbler with the toothed rocker member or possible tendency of the latter to cause the tumbler to again move in a meshing direction.

These and other objects are effected by my invention as will appear from the following

specification and accompanying drawings, forming a part of this application, in which:

Fig. 1 is a plan view of apparatus having my invention applied thereto;

Fig. 2 is a fragmentary sectional view of the apparatus shown in Fig. 1.

Referring now to the drawings more in detail, I show a casing or frame 10, which may be a frame carried by the truck of a railway vehicle, having bearings 11 and 12 for driving and driven shafts 13 and 14, respectively, the driving shaft 13 preferably being the driven shaft of a motor or engine (not shown) and the driven shaft preferably being a load-bearing axle of a truck of a railway vehicle.

The driving shaft 13 has a driving gear 15 mounted thereon and the shaft or member 14 has a driven gear 16 secured thereto. A tumbler gear 17 is maintained constantly in mesh with the driving gear 15 by means of a suitable carrier 18, the carrier 18 confining motion of the tumbler gear 17 to meshed and demeshed positions with respect to the driven gear 16.

In order that the tumbler gear 17 may be translated to a meshing position with the driven gear 16 wholly in consequence of turning of the driving gear 15 in a given direction, for example, clockwise as shown in the drawings, it is necessary that some means be provided to restrain free spinning motion thereof. To this end, I provide a rocker member 20 having teeth 21 and 22 arranged at different radial distances from the axis of its pivot 23. When the tumbler gear and its carrier occupy the demeshed position, the tooth 21 of minimum distance from the axis of the pivot 23 is engaged between teeth of the tumbler gear, the other tooth 22 of greater radial distance from the axis 23 being entirely out of mesh with the tumbler gear or only slightly engaging between teeth thereof.

When the driving gear 15 is turned in a clockwise direction, the tumbler gear 17 is turned in a counter-clockwise direction; and the effect of the engagement of the tooth 21 with the tumbler gear, when the latter is turned in this manner, is to cause the rocker member to tilt downwardly about its pivot 23, with the result that the point of engagement of the tooth 21 with respect to the tumbler is lowered and the tumbler and its carrier are consequently thrust in a meshing direction. After this motion of the tumbler gear and of the rocker 20 has continued to a

suitable extent, the tooth 22 comes into operative engagement with respect to teeth of the tumbler gear and continued rotation of the tumbler gear causes the latter to react on the tooth 22 of the rocker member and to complete its movement in a meshing direction.

As shown in the drawings, the rocker member 20 is provided with a single pair of teeth. For the design shown this number of teeth has been found to be satisfactory; however, it will be understood that any suitable number of teeth may be used dependent upon circumstances. As illustrated, the teeth 21 and 22 are arranged as internal teeth of a segment of a suitable curve, for example, an ellipse; and the pitch curve of these teeth is so disposed with respect to the pivot axis 23 that, when the tumbler gear is in demeshed position and engages the tooth 21, such pitch curve of the teeth of the rocker defines with the pitch circle of the tumbler a downwardly-extending cusp.

The action of the rocker in securing translatory motion of the tumbler gear into mesh with the driven gear is somewhat complex. Such rocker seems to operate somewhat as a toggle and as a rack to utilize a part of the rotary motion of the tumbler gear to secure translation of the latter in a meshing direction. With the rocker member 20 in the position shown in Fig. 1 and with the tumbler gear in demeshed position and engaging the tooth 21, it will be apparent that counter-clockwise rotation of the tumbler gear will cause the rocker member 20 to tilt in a clockwise direction and that the tooth 21 and the engaging teeth of the tumbler gear will define connecting elements of a toggle which is straightened out upon motion of these parts in these directions with the result that the tumbler and its carrier are thrust toward the driven gear 16. Not only does this toggle action come into play for this purpose, but doubtless the translatory action is assisted by the rack-and-pinion action of the tumbler with respect to the tooth 21. After the rocker 20 is tilted in a clockwise direction to a predetermined extent and the tumbler and its carrier have moved in a meshing direction to a corresponding extent, the tooth 22 of the rocker engages with the tumbler for completing the positive translation of the tumbler into meshing relation with respect to the driven gear 16. In operation, it would seem that the tooth 22 acts more after the manner of a rack tooth to secure the translatory effect.

The rocker member 20 is so designed and the gears are so disposed that, when the tumbler gear is turned in a counter-clockwise direction, the latter gear and its carrier will be positively translated in a meshing direction due to coaction of the teeth

21 and 22 of the rocker with the teeth of the tumbler gear and the tooth 22 will be disengaged from the teeth of the tumbler before the latter is entirely meshed with the driven gear. As shown, the tooth 22 does not become entirely free from a space between tumbler teeth until the latter starts to enter spaces between teeth of the driven gear 16; however, it is to be understood that the carrier and the tumbler gear are sufficiently massive to resist forces of spring means, hereinafter described, so that the tumbler gear might be entirely disengaged from the teeth of the rocker member 20 before the teeth of such tumbler are engaged with the driven gear 16, in other words, inertia of the tumbler gear and its carrier may be sufficient to cause the parts to jump between the rocker and the driven gear. This will be apparent when the relative disposition and directions of rotation of the gears are considered.

Since the effect of applying power to the driving gear 15 to move the latter in a clockwise direction is to maintain the tumbler gear 17 forcibly in mesh with the driven gear after the meshing relation of the latter is initially established, it is necessary to provide a means to prevent crowding in of the tumbler gear 17 with respect to the driven gear 16 in order that the latter gears may engage properly with their pitch circles substantially tangent. To this end, I show a suitable stop 24 carried by the frame or support 10 and which is adapted to coact with a projection or abutment 25 carried by the frame 18, the projection 25 coming in contact with the stop 24 to limit inward movement of the tumbler with respect to the driven gear.

As already pointed out, the effect of turning the tumbler gear in a counter-clockwise direction is to cause the rocker member 20 to turn in a clockwise direction during the translation of the tumbler gear; and, after release of the rocker 20 from the tumbler gear, it is necessary that the normal position of such rocker shall be restored. To this end, I show a tension device 26 of any suitable type cooperating with a rod 27 pivotally connected at 28 with respect to the rocker 20 and above the axis of the pivot 23. The tension device acts to pull the rocker member 20 upwardly until the abutment surface 29 thereof comes in contact with an abutment and supporting member 30. It will be noted that the rocker member has a lower abutment surface 30' which is disposed at an angle to the surface 29 so as to permit of the hinging motion of the rocker member 20 about the axis 23 and with respect to the abutment and supporting member 30.

The abutment and supporting member 30 is preferably carried by a suitable tube or barrel 31 connected to the support or frame

10 and spring means 32 are interposed between abutment means 33 at the outer end of the barrel 31 and a suitable collar 34 engaging the abutment and supporting member 30. 5 The spring means 32 therefore, tends to maintain the supporting member 30 in a pre-determined upper position; and, in order that the supporting member 30 may be correctly positioned, I show such member having a stem 35 extending through the collar 34, the spring means 32, and beyond the abutment 33 and having a nut 36 threaded thereto, the nut 36 constituting an abutment element to abut against the outer end of the 15 abutment 33 to limit upward movement of the supporting member. It will be apparent that the position of the supporting member 30 depends upon adjustment of the nut member 36.

20 The abutment member 33 has a threaded connection 37 with respect to the sleeve member 31, whereby such abutment may be turned, not only to vary tension of the spring means 32 but also to vary the position of the 25 supporting member 30.

The purpose of the yieldable support just described for the rocker member 20 is to take care of the condition when tumbler teeth shall abut end to end with the driven gear teeth. 30 Under such circumstances, it will be apparent that translatory motion of the tumbler would be interrupted and the effect of continued tilting action of the rocker 20 would be to apply a powerful reaction against the 35 axis 23; and, if the rocker 20 was fixedly mounted to the frame, there would be danger of breakage of parts. Therefore, I provide the spring or tension means just referred to for supporting the rocker member 20, so that, if the tips of tumbler teeth should abut the tips of driven gear teeth, the effect of continued angular motion of the rocker about its pivot 23 would be merely to push the supporting member 30 downwardly, thereby compressing the spring means. Just as soon as the tumbler gear should be rotated slightly further so that the tips of its teeth would slide off the tips of the driven gear teeth and register with spaces between the latter, the compression already effected in the spring means would cause the latter to act upon the rocker member to quickly move the tumbler teeth into initial engagement.

If the driving gear 15 ceases to be a source 55 of power for the driven gear 16 and the latter gear continues to rotate, as would be the case where that gear is secured to a load-bearing axle of a railway vehicle, such continued motion of the gear 16 has a tendency to kick the tumbler gear 17 out of mesh. 60 This natural tendency is assisted by a spring 39 having one end abutting against the support 10 and the other end abutting against the rocker member 18; this spring being so arranged that its tension is effective nor-

mally to tilt the frame 18 away from the driven gear to demesh the tumbler therefrom. As shown in Fig. 2, the upper end of the spring 39 is arranged about a suitable anchor 40 carried by the supporting frame 10 and 70 the other end of the spring surrounds a movable anchor member 41 hinged at 42 with respect to the lower bridging portion 43 of the carrier 18.

With the apparatus so far described, it is 75 conceivable that the tumbler gear 17 might be disengaged from the driven gear 16 while the driving gear 15 and such tumbler gear are still rotating. This may be due to the inertia of moving parts or perhaps, after 80 cut off, to residual elastic fluid in the driving motor. Such continued rotation of these gears may, due to coaction of the tumbler gear 17 with the teeth 21 and 22 of the rocker, tend to cause the tumbler and its carrier 85 to move in a meshing direction; and, in order to avoid this possibility, I provide damping means to check the rate of movement of the carrier 18 in a demeshing direction in order to assure that, when the tumbler gear reaches its normal demeshed position with the teeth thereof engaging the tooth 21 of the rocker, rotation of the driving gear and of the tumbler gear will be sufficiently checked to avoid any tendency to meshing of 90 the gearing. To this end, I show a dashpot cylinder 44 carried by the frame 10 and having a piston 45 arranged therein, the piston 45 being pivotally connected to a link 46, which, in turn, is pivotally connected to the 100 bridging portion 43 of the frame 18. The cylinder is provided with an inlet check valve 47, whereby, on outward motion of the piston 45, the expansible chamber may be quickly filled with any suitable liquid coming 105 from the supply chamber 48. Upon inward movement of the piston 45, corresponding to demeshing movement of the tumbler and carrier, the valve 47 closes and expulsion of fluid from the cylinder to the supply chamber 48 is confined to the bleeder opening 50. The necessary slow rate of flow through the 110 passage 50, assures that spinning of the tumbler may cease or be sufficiently retarded to avoid any meshing tendency. Although, in 115 practice, the sizes of the bleeder passages would be standardized to secure the desired effect, yet I show a needle valve 51 for the purpose of regulating the rate of discharge. A vent 52 is carried by the upper portion of 120 the chamber 48.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims. 125 130

Having thus described the invention what I claim as new and desire to secure by Letters Patent is:

1. In gearing mechanism, the combination 5 of a driving gear, a driven gear, a tumbler gear constantly in mesh with the driving gear, a carrier for the tumbler gear for confining translatory motion of the latter to meshed and demeshed positions with respect 10 to the driven gear, a rocker member having teeth thereon at different radial distances from the axis of the rocker and the tooth thereof spaced a minimum distance from such axis being adapted to engage between teeth of the tumbler gear when the latter is in its demeshed 15 position, and resilient means for supporting the rocker member.
2. In gearing mechanism, the combination 20 of a driving gear, a driven gear, a tumbler gear constantly in mesh with the driving gear, a carrier for the tumbler gear for confining translatory motion of the latter to meshed and demeshed positions with respect 25 to the driven gear, and a rocker member having a plurality of teeth arranged as an internal gear segment, said teeth being arranged at different radial distances from the axis of the rocker member and the tooth spaced a minimum distance from such axis 30 being adapted to engage the tumbler gear when the latter is in its demeshed position.
3. In gearing mechanism, the combination 35 of a driving gear, a driven gear, a tumbler gear constantly in mesh with the driving gear, a carrier for the tumbler gear for confining translatory motion of the latter to meshed and demeshed positions with respect 40 to the driven gear, a rocker member having a plurality of teeth arranged as an internal gear segment, said teeth being disposed at different radial distances from the axis of the rocker member and the tooth spaced a minimum distance from such axis being 45 adapted to engage the tumbler gear when the latter is in its demeshed position, and resilient means for supporting the rocker member.
4. In gearing mechanism, the combination 50 of a driving gear, a driven gear, a tumbler gear constantly in mesh with the driving gear, a carrier for the tumbler gear for confining translatory motion of the latter to meshed and demeshed positions with respect 55 to the driven gear, a rocker member having teeth thereon disposed at different radial distances from its axis and the tooth spaced a minimum distance from such axis being 60 adapted to engage between teeth of the tumbler gear when the latter is in its demeshed position, resilient means for supporting the rocker member, and resilient means for resisting tilting of the rocker member toward the tumbler gear.
5. In gearing mechanism, the combination 65 of a driving gear, a driven gear, a tumbler

gear constantly in mesh with the driving gear, a carrier for the tumbler gear for confining translatory motion of the latter to meshed and demeshed positions with respect 70 to the driven gear, a rocker member having teeth thereon disposed at different radial distances from its axis and the tooth spaced a minimum distance from such axis being adapted to engage between teeth of the tumbler gear when the latter is in its demeshed 75 position, and resilient means for resisting tilting of the rocker member toward the tumbler gear.

6. In gearing mechanism, the combination 80 of a driving gear, a driven gear, a tumbler gear constantly in mesh with the driving gear, a carrier for the tumbler gear for confining translatory movement of the latter to meshed and demeshed positions with respect 85 to the driven gear, means cooperating with the tumbler gear to secure translatory movement thereof in a meshing direction when the driving gear is turned in one direction, continuously acting biasing means for moving the carrier and the tumbler gear in a demeshing direction, and means for checking motion of the carrier due to the biasing 90 means.

7. In gearing mechanism, the combination 95 of a driving gear, a driven gear, a tumbler gear constantly in mesh with the driving gear, a carrier for the tumbler gear for confining translatory movement of the latter to meshed and demeshed positions with respect 100 to the driven gear, means cooperating with the tumbler gear to secure translatory movement thereof in a meshing direction when the driving gear is turned in one direction, continuously acting spring means cooperating 105 with the carrier and continuously tending to tilt the latter away from the driven gear, and means for dampening motion of the carrier in response to said spring means.

8. In gearing mechanism, the combination 110 of a driving gear, a driven gear, a tumbler gear constantly in mesh with the driving gear, a carrier for the tumbler gear for confining translatory movement of the latter to meshed and demeshed positions with respect 115 to the driven gear, means cooperating with the tumbler gear to secure translatory movement thereof in a meshing direction when the driving gear is turned in one direction, a spring normally tending to tilt the frame away from the driven gear, and dashpot 120 means for resisting such tilting movement of the frame.

9. In gearing mechanism, the combination 125 of a driving gear, a driven gear, a tumbler gear constantly in mesh with the driving gear, a carrier for the tumbler gear for confining translatory movement thereof to meshed and demeshed positions with respect 130 to the driven gear, a rocker member having teeth disposed at different radial distances

from its axis and the tooth at a minimum radial distance being adapted to be engaged between teeth of the tumbler gear when the latter is in its demeshed position, resilient means for resisting tilting motion of the rocker about its axis and toward the tumbler gear while the latter is being translated in a meshing direction and to restore the rocker to a normal position after it is released from the tumbler gear, resilient supporting means

for the rocker, spring means cooperating with the carrier and tending to move the latter away from the driven gear to demesh the tumbler therefrom, and dampening means for checking such motion of the carrier. 15

In testimony whereof I hereunto affix my signature this 5th day of August, 1925.

JAMES P. MADDEN.
